US0D1079334S

(12) United States Design Patent (10) Patent No.: US D1,079,334 S
(45) Date of Patent: * Jun. 17, 2025

(54) DESK

(71) Applicant: ODK TECHNOLOGY PTE.LTD.,
Singapore (SG)

(72) Inventor: Hongbing Zheng, Hangzhou (CN)

(73) Assignee: ODK TECHNOLOGY PTE. LTD.,
Singapore (SG)

() Term: 15 Years

(21) Appl. No.: 29/893,200

(22) Filed: May 26, 2023

(30) Foreign Application Priority Data

Dec. 12, 2022 (CN) 202230830246.7

(51) LOC (15) Cl. 06-03

(52) U.S. Cl.

USPC D6/648; D6/655.1

(58) Field of Classification Search

USPC D6/329, 641, 648-648.2, 649, 652, 655,
D6/655.1, 655.15, 655.18, 655.19, 655.22,
D6/656, 656.16, 656.17, 656.18, 656.19,
D6/708.16

CPC A47B 17/033; A47B 21/06; A47B 83/001;
A47B 21/02

(57) CLAIM

The ornamental design for a desk, as shown and described.

DESCRIPTION

FIG. 1 is a front view of a desk showing my new design;
FIG. 2 is a rear view thereof;
FIG. 3 is a right side view thereof;
FIG. 4 is a left side view thereof;
FIG. 5 is a top view thereof;
FIG. 6 is a bottom view thereof;
FIG. 7 is a front, left and top perspective view thereof;
FIG. 8 is a rear, left and top perspective view thereof; and,
FIG. 9 is a rear, right and bottom perspective view thereof. The broken lines depict portions of the desk that form no part of the claimed design.

1 Claim, 9 Drawing Sheets
